UNITED STATES PATENT OFFICE.

WILLIAM HINDLEY, OF HOBOKEN, NEW JERSEY, AND JOSEPH WM. HARDING, OF NEW YORK, N. Y., ASSIGNEES, BY MESNE ASSIGNMENTS, TO THE DIAMOND WOOD COMPANY OF NEW JERSEY.

WOOD-SAWING MACHINE.

SPECIFICATION forming part of Letters Patent No. 652,772, dated July 3, 1900.

Application filed February 4, 1898. Serial No. 669,070. (No model.)

To all whom it may concern:

Be it known that we, WILLIAM HINDLEY, of Hoboken, in the county of Hudson and State of New Jersey, and JOSEPH WM. HARDING, of New York, (Brooklyn,) in the county of Kings and State of New York, have invented certain new and useful Improvements in Wood-Sawing Machines, of which the following is a full, clear, and exact description.

10 This invention relates to improvements in wood-sawing machines, but more particularly to machines for sawing kindling-wood.

The primary object of the invention is to provide a simple and efficient machine adapted to receive long bundles of wood bound at stated intervals, which will carry the bundles forward, and which will hold and cut the bundles between the bindings, so as to secure a series of separate and independent smaller 20 packages of kindling-wood ready for the market.

A further object of the invention is to provide simple and efficient mechanism for operating the several parts and to provide a 25 machine which may be used for various purposes.

With these and other objects in view the invention consists in the construction and combination of the several parts, substantially 30 as hereinafter described and then pointed out in the claims at the end of the description.

Referring to the accompanying drawings, forming a part of this specification, wherein similar figures of reference designate similar 35 parts, Figure 1 is a side elevation of one form of the machine embodying our invention. Fig. 2 is a sectional plan view, partly broken away, taken on the line II II of Fig. 1. Fig. 3 is a vertical transverse section, partly 40 broken away, taken on the line III III of Fig. 2. Fig. 4 is a fragmentary longitudinal vertical section taken on the line IV IV of Fig. 3, and Fig. 5 is a fragmentary detail view illustrating means for imparting a vertical 45 movement to the saws.

The frame may be of any desired form and may consist of sections 10 and 10^a, suitably bolted and secured together, in the former of which are journaled the transverse shafts 11 50 and 12. On each of these transverse shafts

is secured a drum 13, provided at intervals with sprocket-teeth which engage the links of the endless chains or carriers 14, though instead of the drums a series of sprocket-wheels may be employed corresponding in 55 number to the number of endless chains or carriers with which they engage. On the chains 14 are arranged at stated intervals are buckets or jaws 15, which may be secured to or formed as a part of one of the connecting-links, said jaws being substantially U-shaped in cross-section and having the upper portion thereof concaved, so as to conform, substantially, to the contour of the periphery of the long bundles of wood 15^a. 60

The shaft 12 has a pinion 16 secured at one end thereof, which meshes with a gear 17, secured to the stud or shaft 18, and rotating with the gear 17 is a ratchet-wheel 19, normally engaged by a spring-pressed pawl 20, 70 pivoted to the arm 21, the latter having one end journaled loosely on the shaft or stud 18 and its other end provided with a stud or pin 21^a, on which may be arranged a roller normally in engagement with the grooved cam 22. 75 This cam 22 is secured to the shaft 23, on which may be arranged a drive-pulley 24, so that when the latter is rotated the cam 22 will rock the arm 21 on its pivot and through the pawl-and-ratchet and gear mechanism already described will impart an intermittent movement to the drums 13 and the endless chains or carriers 14, so as to carry the bundles of wood forward the distance between any two series of jaws or buckets 15 at each 80 revolution of said cam.

The bundles of wood 15^a as they are dropped into the buckets 15 assume the position shown to the right in Fig. 1, and as the chains 14 and buckets 15 are advanced the wood will 90 contact with a suitable engaging device. As shown, this device comprises a series of rollers 25, which are arranged to rotate with the transverse shaft 26 (shown in Figs. 1 and 2) in order that the bundles of wood when engaged by the rollers may be forced or rocked so as to assume the position shown in full lines in Fig. 4. For the purpose of holding the bundles while being cut or separated we may provide a movable head or clamping device 95 100

27, arranged to slide in the sections 10^a of the frame, and on the under side of said head, between the sections of the frame are arranged a series of clamping-jaws or buckets 28, corresponding in form to the buckets or jaws 15. These jaws 28 have their concaved portions opposed to the concaved portions of the buckets 15, so as to substantially surround the bundle when the latter is clamped or held stationary, and said buckets may be either formed on the head 27 or secured thereto by bolts 29, as shown in the drawings. To the outer ends of the clamping-head 27 may be secured the rods 30, which are guided in the bosses 31 on the sections 10^a of the frame and have their upper ends pivoted to rock-levers 32, the latter having one end thereof connected to the links 33, pivoted to the sections of the frame, and their other ends connected to vertically movable connecting-rods 34. These connecting-rods have their lower ends pivoted to arms or levers 35, secured to the transverse shaft 36, one of said arms being extended so as to form a bell-crank lever and provided at its upper end with a roller 36^a, which normally engages a cam-groove in the cam 37, which is secured to a stud or shaft 38. On the shaft 38 is arranged a gear 39, which meshes with an idler 40 on the shaft 12, which in turn meshes with an idler 41, the latter being in mesh with the gear 42, secured to the drive-shaft 23, so that when the latter is rotated the train of gearing will impart a rotary movement to the shaft 38. This shaft 38 is properly timed with respect to the intermittent movement of the sprocket-drums 13, and when rotated said shaft, through the cam 37, roller 36^a, arms 35, connecting-rods 34, and its connections, will impart a vertical movement to the clamping-head 27. A series of grate-bars 43 are arranged below the head 27, forming a stationary bed over which the chains 14 are adapted to pass in order to form a support for the chains carrying the buckets or jaws when the clamping-head 27 is forced downward to hold the bundle of wood. These grate-bars may be secured to T-shaped cross-bars, as 44, secured to the sections 10 of the frame, though instead of the grate-bars any suitable bed may be provided.

The saws 45 may be of any desired number and are arranged on the transverse shaft 46. These saws are separated by suitable collars 47 and are rigidly clamped together by the lock-nuts 48, the saws being arranged on the shaft so as to enter the spaces between the grate-bars 43 and the chains of the carriers 14. The shaft 46 is journaled in the cross heads or slides 49, which are adapted to move back and forth in the sections 10 of the frame, and the shaft 46 is connected to the links 50, the outer or forward ends of which are pivoted to the arms 51. These arms are secured to the transverse shaft 51^a, one of which arms is connected by a rod 52 to a rock-

arm 53, loosely arranged upon the transverse shaft 36. This arm 53 may have a suitable roller which engages a cam-groove in the cam 54, the latter being secured to the shaft 38, so as to rotate with the cam 37. By this means the saws are moved inwardly toward the clamping-head 27, so as to divide the long bundle into independent smaller bundles or packages 15.

The saws 45 may be rotated in any desired manner. As shown, the shaft 46 has a pulley 55 at one end thereof, around which passes a belt 56, which is rotated by the pulley 57, the latter being suspended by movable links 58, arranged on the shaft 59. The links 58 are connected to the shaft 46 by the connecting-rod 60, so that the shafts of the pulleys 57 and 55 will remain a fixed distance apart. To the shaft of the pulley 57 is secured a pulley 61, which is rotated by a belt 62, which passes around the pulley 63, arranged on the shaft 59, the latter shaft being suitably suspended and rotated by means of the drive-pulley 64. The arrangement of the links 58 permits the shaft 46 to be constantly rotated while being moved lengthwise of the machine.

The operation of the invention will be readily understood from the foregoing description when taken in connection with the accompanying drawings.

The bundles of wood being deposited in the buckets or jaws 15 in any suitable manner and the pulley 42 rotated, it will be seen that the cam 22 will rock the arm 21 on its pivot, and through the pawl 20, ratchet-wheel 19, gear 17, and pinion 16 an intermittent movement will be imparted to the shaft 12, drums, and endless chains 14, thus advancing the bundles in the buckets or jaws. As the chains advance the bundles contact with the rollers 25 on the transverse shaft 26, so as to be forced to the position shown in Fig. 4. This intermittent movement continues until one series of buckets are in alignment with the clamping-head 27. The head is now moved downward by the rods 30, levers 32, connecting-rods 34, arms 35, and cam 37, which latter is rotated by the train of gearing from the shaft 23, as hereinbefore described. While the bundle is clamped between the jaws 15 of the chain, which is supported by the grate-bars of the bed and the jaws 28 of the clamping-head 27, the saws 45, which are rotated by the driving mechanism heretofore referred to, are moved inwardly toward the head to the position shown in the drawings by the links 50, arms 51, connecting-rod 52, rock-arm 53, and cam 54, thus separating the bundle of wood into a number of smaller and independent packages. The clamping-head 27 is now raised by the mechanism already described. The saws 45, through the links 50, arms 51, and their operating mechanism, are then carried outwardly away from the head 27 to permit the next long bundle of wood to be divided, so as to be placed under the clamping-head. Simultane-

ously with the outward movement of the arms 45 the drums 13 and chains 14 are given an intermittent movement, so as to place the next bundle in position for the clamping-head to engage and rigidly hold the same for the next inward movement of the saws 45. The operation is repeated, and the divided bundles are carried outward by the carriers or chains, and, as the buckets rotate around the drum 10 on the shaft 11, may be removed or they will be dropped on the floor, as shown in Fig. 1, or into a suitable receptacle provided therefor, as desired.

We thus provide an efficient machine which 15 will carry the long bound bundles of wood forward, hold and cut the same between the bindings ready for the market, and after being cut the smaller bundles will be carried outwardly, so as to be readily removed or 20 dropped into a suitable receptacle provided therefor.

While we have described mechanism for intermittently moving the carriers or chains as a part of the machine, we may arrange said 25 or similar mechanism on a suitable bundling-machine, such as described in our pending application, Serial No. 658,256, filed November 12, 1897. When used in this manner, the chains or carriers are arranged so that 30 the long bundles of wood when bound will drop from the binding mechanism directly into the buckets or jaws 15.

In some instances it may be found desirable to move the saws vertically instead of horizontally, as shown in Figs. 1 to 3, inclusive. 35 In such case the saws may be suspended from an oscillatory lever or arranged as shown in Fig. 5. Here the shaft 46 is journaled in the cross-heads 65, which are vertically movable 40 in the sections 10 of the frame and are connected to the links 66, only one section of the frame and the connecting parts being shown. The links 66 are connected at one end to levers 67, one of which connects to a rod 68, the 45 latter being operated in a similar manner to the rod 52, (shown in the other figures,) so that as the levers 67 are rocked on their pivots the saws, through the links 66, will be given a vertical movement. When thus arranged, 50 the saws may be carried away from the path of movement of the bundles after the same have been cut and before the clamping head or device 27 is released.

It will be readily seen that other clamping 55 means than the head may be employed, that any desired form or construction of saw or saws may be used, and that some of the parts may be dispensed with or others substituted therefor without departing from the spirit of 60 our invention.

Having thus described our invention, we claim as new and desire to secure by Letters Patent—

1. A wood-sawing machine, comprising a series of intermittently-moving jaws or buckets shaped to fit the stock, the jaws of the several series being held in parallel relation, a second series of vertically-movable jaws also shaped to fit the stock and adapted to close over the same when the traveling jaws 70 are at rest, and a series of rotatable saws movable between the jaws and in the path of the stock, substantially as described. 65

2. A wood-sawing machine, comprising a series of intermittently-movable chains, each 75 having buckets or jaws at stated intervals thereon, the said jaws being shaped to fit the stock and arranged with the jaws of one series parallel with those of adjacent series of chains, vertically-movable and similarly-shaped jaws adapted to close over the stock 80 opposite one of the traveling series of jaws when the latter are at rest, and a gang of rotary saws arranged in the path of the stock and between the series of jaws, substantially as described. 85

3. A wood-sawing machine, comprising a series of intermittently-movable chains, buckets or jaws arranged at intervals on the chains, the jaws of one chain parallel with those of 90 adjacent chains, the said jaws being shaped to fit the stock, similarly-shaped vertically-movable jaws adapted to close over the stock in the traveling jaws when the latter are at rest, and a gang of rotary saws arranged in 95 the path of the stock and between the jaws, the said saws being movable backward and forward in relation to the stock, substantially as described.

4. In a machine of the kind described, the 100 combination with the series of traveling jaws shaped to fit the stock when the latter is in a certain position and arranged in parallel relation, of automatic means for tilting the stock into its fitting position in the jaws, a 105 second series of vertically-movable jaws adapted to fit over the stock and bind it in the traveling jaws, and saws arranged in the path of the stock, substantially as described. 110

5. The combination with the intermittently-moving parallel series of jaws shaped to fit the stock when the latter is in a certain position, of means as the series of rollers arranged in the path of the stock to tilt it into its best position in the jaws, a second series 115 of vertically-movable jaws adapted to close over the stock and bind it to the traveling jaws, and a gang of saws arranged to sever the stock between the jaws, substantially as described. 110
